UNITED STATES PATENT OFFICE.

WILLIAM PHENIX, OF CHICAGO, ILLINOIS.

TENSION APPLIANCE FOR TRACTION-CABLES.

SPECIFICATION forming part of Letters Patent No. 397,611, dated February 12, 1889.

Application filed August 21, 1888. Serial No. 283,308½. (No model.)

To all whom it may concern:

Be it known that I, WILLIAM PHENIX, of Chicago, in the county of Cook and State of Illinois, have invented certain new and useful Improvements in Tension Appliances for Traction-Cables, of which the following is a full, clear, and exact description, that will enable others to make and use the same, reference being had to the accompanying drawings, forming a part of this specification.

The object of this invention is to provide a device for taking up the slack of traction-cables, and is so constructed and arranged as to maintain a constant and uniform tension or strain on both sides of the endless cable alike. This device is more especially intended for use at the foot of steep hills or heavy grades.

Figure 1 is a plan or top view of my improved appliance; Fig. 2, a side elevation, the inclosing-wall being removed; and Fig. 3, a vertical section through the hub of the cable-tension wheel and slide.

In the drawings, A represents the cable-tension sheave-wheel; A', the traction-cable; A², the chamber below the surface in which said wheel is placed; A³, the weight-pit, and A⁴ the wall inclosing said chamber and pit.

The cable sheave-wheel A is set at an angle, the degree of inclination being in accordance with the grade or slope of the road-bed. This wheel is loosely mounted on the stationary shaft B, the cap a, removably secured to the upper end of said shaft, serving to retain the wheel A in its proper position. The hub a' of the slide C is rigidly mounted on the lower end of the vertical shaft B. The upper end of the hub a' is provided with the vertical annular rim a², which engages loosely with the corresponding recess, a³, in the under side of the hub a' of the wheel A, as shown in Fig. 3. This arrangement permits of the tension-wheel rotating freely, but locks the same into engagement with the slide C, so as to follow the movements of the same. The two edges of the slide C engage with the guides a⁵ a⁶, provided with the rabbeted grooves a⁶ a⁶, as shown in Fig. 3. These guides are supported at one end by being bolted to the transverse angle-bar b, (see Fig. 1,) while the opposite

ends rest upon one side of the wall inclosing the weight-pit and are secured thereto by bolts embedded in the masonry, as indicated by dotted lines in Fig. 2. The guides a⁵ are provided near their outer ends with the stop-lugs b', which limit the travel of the slide C in that direction, the bar b serving the same purpose on the opposite end. 55

b² is a draw-bar attached to the slide C, and b³ an evener-bar pivoted transversely to the projecting end of the draw-bar, as shown in Fig. 1. To the respective ends of the evener-bar are connected the tension-weight cables b⁴ b⁴, which pass over the vertical companion sheaves b⁵ b⁵ and down into the pit and connect with the ends of the second transverse evener-bar b⁶, which is pivoted at its longitudinal center to the head d on the vertical rod supporting the weight D. The sheaves b⁵ are pivoted with suitable journal-bearings 70 and supported in the mouth of the pit by the beams d' d'. 65

In operation the slide C moves back and forth as the strain on the traction-cable is diminished or increased, the evener-bars and double-weight cables serving to instantly respond to and regulate the uneven or irregular strain on the two sides of the endless traction-cable. This arrangement provides a simple and convenient appliance for the purpose set 80 forth, and one that can be used where the ordinary devices would not be applicable. 75

Having thus described my invention, what I claim as new, and desire to secure by Letters Patent, is—

1. In a tension appliance for traction-cables, the combination, with the slide C, the hub whereof is rigidly mounted on the shaft B and provided on the upper end with the vertical annular rim a², of the tension-wheel A, loosely 90 mounted on the upper end of the shaft B, the hub whereof is provided with an annular recess, with which the rim a² loosely engages, substantially as set forth.

2. In a tension appliance, the combination, 95 with the traction-cable, of a tension sheave-wheel arranged in an inclined horizontal position, the shaft B, upon the upper end of which said wheel is loosely mounted, the slide C, arranged underneath said tension-wheel 100

and rigidly mounted on the lower end of said shaft, means for supporting said slide, the draw-bar b^2 , the evener-bar b^3 , the weight-cables b^4 b^4 , connected by their upper ends to 5 the respective ends of the evener-bar b^3 , the vertical companion sheaves b^5 b^5 , the evener-bar b^6 , to the respective ends of which are connected the lower ends of the weight-cables b^4 b^4 , and the weight D, suspended from the longitudinal center of said evener-bar, substantially as and for the purpose set forth.

3. In a tension appliance for traction-cables, the combination, with the slide C, of the guides a^5 a^5 , provided near one end with the stop-lugs, and the angle-bar b, supporting the opposite ends of said guides, substantially as and for the purpose set forth. 15

WILLIAM PHENIX.
